ASSIGNOR TO SAID SEWARD.

CAR-COUPING.

1,280,330.

Specification of Letters Patent.

Patented Oct. 1, 1918.

Application filed July 3, 1917. Serial No. 178,477.

To all whom it may concern:

Be it known that we, JOHN H. TAYLOR and FRANK J. C. SEWARD, citizens of the United States, residing at Peoria, in the county of Peoria and State of Illinois, have invented certain new and useful Improvements in Car-Couplings; and we do hereby declare that the following is a full, clear, and exact description of the invention, which will enable others skilled in the art to which it appertains to make and use the same.

This invention relates to improvements in car couplings.

It has for one of its objects to provide a coupling that will be notable for its ease and positiveness of operation in both the coupling and uncoupling action.

Another object is to provide a coupling of the nature described wherein the tail of the usual knuckle includes two portions lying in different horizontal planes, and a locking member adapted after the uncoupling operation to rest on the upper of the two portions of the tail, the tail in the coupling operation passing from beneath the member to permit said member to drop to the locking position.

Another object is to provide a structure in a car coupling in which the knuckle will be positively thrown to the unlocking position with the least amount of effort, the latter resting upon the knuckle while in the unlocked or open position, said locking member upon movement of the knuckle to its coupling position being liberated to drop down into position to lock said knuckle.

Besides these objects the invention relates to certain details of construction to be pointed out herein and in the accompanying claims, aided by the appended drawing, which shows the preferred embodiment of the invention, though it is to be understood that slight changes may be made, such as will fairly fall within the meaning of the invention and the scope of the claims.

Figure 1 is a plan of the coupling, showing the knuckle in its open position.

Fig. 2 is a horizontal section of the draw-head, above the knuckle.

Fig. 3 shows the knuckle and a part of the locking member in perspective.

Fig. 4 is an elevation of an operating member shown in part section.

Fig. 5 shows a locking member in perspective.

Fig. 6 is a longitudinal sectional elevation

of the draw-head showing the relation of the several operating parts therein.

1 is the draw-head including the usual shank 2 for attachment to the car. Said draw-head in general outline and dimensions corresponds to those in common use but its cavity differs in its form to accommodate the form of knuckle, and the form of locking member included in my invention.

The cavity is denoted by the reference character 3 into which the knuckle extends. The draw-head has an upper and a lower extension 4 and 5 respectively, Fig. 6, between which is pivoted the said knuckle indicated as a whole by 6, the pivot member being indicated as a pin at 7.

The outer coupling portion 8 of the knuckle is substantially identical in form with those now in almost universal use while that part within the draw-head comprises a tail piece whose longest measurement lies at a slight angle to the longest measurement of the described coupling portion 8, said angle being an acute one. Said tail piece comprises an upper and lower part 9 and 10, one offset from the other as clearly shown. The part 9 is flat on its upper surface, its end surface by preference describing an arc struck from substantially the center of the pin 7 also by preference. The part 10 lies lower than the described part 9 and extends beyond the end thereof into a point 11; also said part 10 extends laterally from the part 9. The rear edge of the part 10 or that facing the rear wall of the cavity is carried forward to or beyond the rear face of the part 9 substantially in the manner shown.

The described cavity 3 has a deepened rearwardly extending communicating cavity 12. 13 indicates as a whole a locking member shown in full in Fig. 5, lying in said cavity 12. It comprises an upper head portion 14 including at one corner a point 14' and includes also at two of its sides opposite said point a depending extension 15 creating a cavity 16. 17 is a depending finger at one corner of the head 14 which curves forwardly substantially at an angle of 45° to the longitudinal line of the draw-head, slanting downward at an angle and terminating in a vertical portion 18. This finger is adapted to move vertically within a slot 19 in the bottom of said draw-head.

The locking member slidably fits the recess 12, being adapted to move vertically

therein and has an upstanding ear 20. 21 is an operating member therefor vertically slidable within a hole 22 in the top wall of the draw-head, which operating member is slotted at 23, a pin 24 in the ear 20 engaging in said slot.

The locking position for the knuckle is clearly indicated in Fig. 2, wherein the part 10 lies within the cavity 16, it being understood that the coupling member in that figure is shown in horizontal section just above said cavity or on line $a-a$, Fig. 5. Said member being confined between the walls of the cavity 12 is, of course, immovable in a lateral direction, and as the point 11 of the knuckle lies in the cavity, said knuckle is firmly and immovably locked in the coupling position.

The uncoupling operation on that of releasing and throwing out the knuckle is accomplished by lifting the operating member 21. Since the locking member is connected with it that member is also raised so that the depending extension 15 is raised 25 clear of the part 10, after which the downwardly and forwardly inclined finger 17 engages behind the point 11 of said part 10 and in the raising movement of the finger the inclining upper surface in the lifting movement readily and positively moves the knuckle to its open position, following in behind it. The extent of opening movement of the knuckle is limited by the heel of the portion 8 meeting the outer surface 35 of the draw-head, Fig. 1, but other means of limiting the movement may, of course, be used.

As this limit of opening movement is reached a portion of the part 9 of the knuckle, as shown in Figs. 1 and 3, remains beneath the corner portion or point 14 of said locking member, and that member when released rests thereon until the portion 9 of the opposite coupling, not shown, enters the 45 draw-head and strikes the part 10 of the knuckle whereupon said knuckle is returned to its locking position, the said part 10 being pushed from under the head 14. When that movement is completed the part 10 is 50 then directly beneath the cavity 16 of the locking member and the latter then drops to the position shown in Fig. 6 upon said member 10, the parts then having again assumed the relation illustrated in Fig. 2.

55 The point 14 of the head 14 is of sufficient length to remain upon the part 9 until the said point 11 has nearly reached its final position so that the point 11 can pass beneath the extension 15.

60 The operating member 21 since slotted can always drop to its position shown in Fig. 6 due to the slot 23 regardless of the position of the locking member whether raised or lowered and can never interfere with the operation of the latter besides act-

ing somewhat as a guide for the same. The walls of the locking member within the recess 16 substantially conform to the contour of the point or extension of the part 10 so that while the parts can be freely engaged and disengaged there will be no great amount of looseness.

Our structure differs from those of which we are aware in so disposing the finger 17 that when raised to unlock and throw out the knuckle it will engage the tail of the knuckle at its free end far removed from the pivot. By reason of this the leverage thus obtained permits the knuckle to be thrown open with a minimum of effort. In fact, the mere lifting of the weight of the locking member is practically the only effort required, it being found that it can be raised by the hand to throw open the knuckle as readily as through the intermediary of the hand lever ordinarily employed for the uncoupling operation.

Again, the finger 17 at all times is suspended, *i.e.*, it is not supported nor does it rest at any time upon any part of the head as in older structures of which we are aware. That is to say, in many of the common forms of couplings the finger after throwing the knuckle lies upon a portion of the head behind said knuckle and in the coupling operation must be pushed out of the way dragging across and upon said portion. The finger is thus often broken besides endangering the other parts of the coupling.

The point 11 of the knuckle is provided in order that the finger will engage behind it and force the knuckle to the open position by following in behind it to the full limit of movement of the knuckle, said finger then dropping entirely out of the way within the slot 19. Said finger does not at any time lie in the path of the knuckle in the coupling action.

Having thus described our invention, we claim:

1. In combination, a draw-head, a knuckle pivotally mounted therein having a tail portion including two extensions, each in a different horizontal plane, one being longer than the other and extended laterally therefrom, a locking member vertically movable in the head including a part to lie upon the short extension in the open position of the knuckle, there being a recess in said locking member beneath the part to receive the long extension in the closed or locking position of said knuckle.

2. In combination, a draw-head, a knuckle pivotally mounted therein having a tail portion including two extensions, each in a different horizontal plane, one being longer than the other and extended laterally therefrom, a locking member vertically movable in the head, said head including in its construction a vertical guide for the said mem-

- ber, the latter including a part adapted to normally lie upon the short extension for holding the member raised in the open positions of the knuckle and including also a 5 depending portion to receive the long extension against it in the locking position of the knuckle, there being a recess in said member beneath the part to receive said long extension.
- 10 3. In combination, a draw-head, a knuckle pivotally mounted therein having a tail portion including two extensions, each in a different horizontal plane, one being longer than the other and extended laterally there- 75
- 15 from, a locking member vertically movable in the head, said head including in its construction a guide for the said member, the latter including a part normally lying upon the short extension holding the member raised 80
- 20 free of the long extension in the open position of the knuckle and adapted to pass off said extension in the closing movement of the said knuckle as the long extension reaches substantially the end of that move- 85
- 25 ment for locking the knuckle.
4. In combination, a draw-head, a knuckle pivotally mounted therein having a tail portion including two extensions, one being longer than the other, and one of them ex- 90
- 30 tending laterally from the other both lying in different substantially horizontally planes, and a locking-member adapted to lie upon one of the extensions and suspended above the other extension in the open position of 95
- 35 the knuckle arranged and adapted in the closing movement of said knuckle to drop behind the said other extension.
5. In combination, a draw-head having a vertically arranged guide portion, a knuckle 100
- 40 pivotally mounted therein having a tail portion including two extensions, one being longer than the other and projecting laterally at one edge beyond one of the edges of the other, the extensions lying in different 105
- 45 horizontal planes, the short extension moving in advance of the other in the closing movement of the knuckle, and a locking- member vertically movable in said guide portion including a part to lie upon the 110
- 50 short extension and also including a depending portion adapted to engage the long extension in the locking position and suspended above the path of the last named extension in the open position of the knuckle.
- 55 6. In combination, a draw-head, a knuckle pivotally mounted therein having a tail portion including two extensions, one being longer than the other and projecting laterally at one edge beyond one of the edges of 115
- 60 the other, both lying in different horizontal planes, the short extension moving in advance of the other in the closing movement of the knuckle, and a locking-member vertically movable in said guide portion includ- 120
- 65 ing a part to lie upon the short extension 125
- and also including a depending portion adapted to engage the long extension in the locking position and suspended above the path of the last named extension by the said short extension in the open position of the 70 knuckle, the locking member including a depending finger extending forwardly in the direction of the knuckle.
7. In combination, a draw-head, a knuckle pivotally mounted therein having a tail por- 75
- tion including two extensions lying in different horizontal planes, and a locking- member having a part adapted in one of the extreme positions of the knuckle to rest upon the upper of the extensions and also 80
- having a part adapted in the other extreme or locking position of said knuckle to lie behind the lower extension.
8. In combination, a draw-head, a knuckle pivotally mounted therein having a tail por- 85
- tion including two extensions lying in different horizontal planes, a guide portion in the said head and a locking-member having a part adapted in one of the extreme positions of the knuckle to rest upon the 90
- upper of the extensions and also having a part adapted in the other extreme or locking position of said knuckle to lie behind the lower extension, said member including a finger extending downwardly and 95
- forwardly in the direction of the knuckle.
9. In combination, a draw-head, a knuckle pivotally mounted therein including a tail portion having an elongated part lower than the balance of said tail piece, and a 100
- locking-member of a single part adapted to rest upon the tail portion in the open position of the knuckle and including a depending portion normally overhanging the elongated lower portion in said open position adapted in the closing movement of the knuckle to drop down behind the said elongated lower part and hold the knuckle 105
- in its locked position.
10. A car coupling including in its con- 110
- struction, in combination, a draw-head having a cavity in its rear wall communicating with the main cavity of said head, a knuckle having a tail portion including two parts disposed in different parallel planes, 115
- said parts being offset laterally from one another, one being longer than the other, a locking member adapted to move vertically within the first said cavity comprising a member having a recess therein and a portion overhanging said recess, the longer portion of the tail of the knuckle adapted to engage in said recess in the coupling position.
11. A car coupling including in its con- 120
- struction, in combination, a draw-head, a knuckle having a tail piece provided with two extensions, one being greater in length than the other, a locking member adapted to lie in the path of the long extension and 125
- 130

- including a finger to engage the same, the member being supported on the short extension out of the path of the said long extension in the open position of the knuckle.
- 5 12. In combination, a draw-head and a knuckle pivoted therein including a tail portion composed of two extensions arranged in different horizontal planes, one of said extensions being greater in length than the 10 other measured from the pivot to each outermost extremity, the longest one having a part extended laterally from and having a surface lying lower than that of the other, a vertically movable locking member including 15 a part to lie upon the upper short extremity in the open position of the knuckle, and having also a depending extension normally suspended above the long extremity and adapted in the closing movement of 20 said knuckle to drop and engage behind said long extremity and maintain the knuckle in its locked position.
13. In combination, a draw-head and a knuckle pivoted therein including a tail portion composed of two extensions, one being greater in length than the other measured from the pivot to each outermost 25

extremity, the longest one having a part extended laterally from and below the other, a vertically movable locking member including 30 a part to lie upon the upper short extremity in the open position of the knuckle, and having also a depending extension normally suspended above the long extremity and adapted in the closing movement of 35 said knuckle to drop and engage behind said long extremity and maintain the knuckle in its locked position, said locking member having a depending finger.

14. As a new article of manufacture, a 40 knuckle for a car coupling including an outer coupling portion and a tail portion comprising an upper and lower extension, the lower one being extended laterally from 45 the upper one and being greater in length than the same.

In testimony whereof we affix our signatures, in presence of two witnesses.
